OSCAR H. DICKE, OF ROCHESTER, NEW YORK, ASSIGNOR TO GENERAL RAILWAY SIGNAL COMPANY, OF ROCHESTER, NEW YORK

SIGNALING SYSTEM FOR RAILROADS

Application filed August 16, 1929. Serial No. 386,301.

This invention relates to railroad signaling and interlocking systems and more particularly to means for safely indicating the position of a distant track switch and a switch machine controlling such track switch.

It is understood by those skilled in the art of railway signaling that it is very important to definitely indicate the position of a distant track switch in an interlocking system, this by reason of the fact that signals of a particular route should not be permitted to indicate such route if there is a conflicting route set up.

In accordance with the present invention it is proposed to indicate over the same circuit the condition of a distant track switch by applying alternating current of a polarity corresponding to the position of the track switch, and in including in said circuit a rectifier element which is poled in a direction to correspond to that of such track switch. In other words, the indicating means according to the present invention resides in the transmission of pulsating current of a particular polarity and a particular phase relation. Another object of the present invention is to apply the polarity of the alternating current in accordance with one device, such for instance, as a switch machine, and to insert a rectifier poled in accordance with some other device such as the switch points or by two different devices such as the switch points at opposite ends of a crossover, and a like.

Other objects, purposes and characteristic features of the invention will in part be obvious from the accompanying drawings and will in part be pointed out in the specification hereinafter.

In describing the invention in detail reference will be made to the accompanying drawings, in which the apparatus in the dotted rectangle represents the apparatus in an interlocking tower, and the remaining apparatus conventionally shown is that located at a distant way station.

Referring to the drawings the rails 1 of the main track of a railway system have been shown divided into track sections by insulating joints 2, and these rails 1 are at times

connected to the siding including rails 3, through the medium of a track switch S. Associated with this track switch S is an east-bound main signal ME, an east-bound dwarf signal DE, a west-bound main signal MW and a take-siding signal DW. In the arrangement shown, the track switch S is operated by a switch machine SM and operates the switch box contacts 5 and 6. This switch machine SM is controlled from the interlocking tower T through the medium of the lever L and suitable control circuits conventionally indicated by the dotted line 7.

In the dispatcher's office is located suitable indicating means, which in the particular embodiment illustrated comprises polyphase alternating current three-position relay AC and a three-position direct current polar relay DC, connected in series. The relay DC is preferably shunted by a condenser 8 of large capacity, so that a large portion of the alternating current may pass through this condenser 8 rather than through the relay DC. These indicating relays AC and DC are at times supplied with energy from the distant way station through the medium of transformer 10 and the rectifier R. Although this rectifier R may be one of the electrolytic or thermionic type, it is preferably a rectifier of the copperoxide type, which latter type has a lower leakage resistance in the reverse direction therethrough. Having now described the elements of the system, it is believed expedient to consider the operation thereof, and the features of safety afforded thereby.

Operation.—In the apparatus as illustrated in the drawings the track switch assumes the main track position, and with the switch machine indicating contacts 11 and 12 properly adjusted and with the throw rod and indicating rod properly intact, so that the switch box contacts 5 and 6 assume their proper position, renders the following indicating circuit complete:—beginning at the secondary winding of the transformer 10, wires 15 and 16, switch machine contact 11, wires 17 and 18, switch box contact 5, rectifier R, switch box contact 6, indicating wire 20, through relay DC insofar as direct current 100

component is concerned and through the condenser 8 insofar as the alternating current component is concerned, wire 21, control winding of the relay AC, wire 22, common return wire C, wire 23, switch machine contact 12, wire 24, back to the secondary winding of transformer 10. The flow of pulsating current of a particular polarity, as determined by the rectifier R, and of a particular phase relation as determined by the pole changing contacts 11-12, causes the DC relay to assume its right-hand position by reason of the polarity of the direct current component and causes the relay AC to assume the right-hand position by reason of the phase relation of the alternating current component co-acting with the flux of the local winding 25 of this relay AC.

It should be noted that the local winding 20 25 of the relay AC is connected to the same trickle-charge transmission line 26 as is the transformer 10. With the relays AC and DC both energized as just explained, the contacts 27 and 28 of these relays AC and DC, respectively, assume their right-hand position and close a circuit to levers for controlling non-conflicting signals, such as the signals ME and MW, as indicated by the legend. In this connection it may be pointed out that 30 these contacts 27 and 28 may also supply energy to levers controlling other traffic controlling devices which are non-conflicting and which are associated with the track switch S, as would be the case in a large interlocking plant.

Attention is now directed to the feature of safety of the system embodying the present invention. Obviously, a cross between the indicating line 20 and the common return wire C would not cause a false indication, because the relays AC and DC would, if anything, both be shunted and de-energized by such cross. Should a cross occur between the wires 17 and 23, this cross would also de-energize the relays AC and DC. Should a cross occur between the wires 17 and 20, this rectifier R would be shunted out and the relay DC would assume its de-energized position. This of course would cause the contact 28 to assume its pendant position, thereby opening the circuit to the lever controlling signals ME and MW. Should direct current be applied to the indicating wire 20 through some unauthorized path, it could produce no other effect than effect de-energization or reverse energization of the relay DC, and if this should happen no false indication could result, in that it requires both the relays AC and DC to assume corresponding positions 50 in order to complete an indication circuit. Similarly, should alternating current of the same or some other frequency or the same or some other phase relation be applied to the indicating wire 20, this alternating current 55 could only effect the relay AC, and therefore

could not result in the closure of a false indication circuit.

In other words, in order to give a false indication it would be necessary for the circuit heretofore traced to be broken at some 70 distant point and have both direct and alternating unauthorized current of proper potential and proper polarity and phase relation to be applied to the indication line 20 at the same time, and this is a very remote 75 possibility, and in practice could be easily avoided by careful construction and insulation of the circuits and apparatus.

Let us now assume that the lever L is operated to its reverse position and that this 20 results in operation of the switch machine to its reverse position. By studying the circuit heretofore traced, it becomes apparent that reversal of the switch machine SM reverses the instantaneous alternating current 85 polarity, by reversing the connections of the transformer 10 in the indication circuit, and that movement of the switch points to the take-siding position reverses the pole changing switch box contacts 5 and 6, thereby reversing the polar arrangement of the rectifier R in said circuit. In other words, should the throw rod of the switch machine SM be broken, so that operation of the switch machine SM reverses the alternating current 90 polarity but the rectifier R is not reversed in the circuit, only the alternating current relay AC would be moved to its left-hand position in which event neither of the circuits leading to the signal levers would be closed. From this it seems that the switch box contacts 5 and 6 must be in a position corresponding to the position of switch machine contacts 11 and 12, in order to energize the 95 relays AC and DC to corresponding positions. In the event, that the contacts 11 and 12 are applied to one set of switch points of a cross over, and the contacts 5 and 6 are applied to the other switch points of the same cross over, it becomes apparent that the two 100 switches of the cross over must be in corresponding positions in order to cause both of these relays AC and DC to assume corresponding positions and render the indication 105 complete.

Having thus shown and described one specific embodiment of the present invention, it is desired to be understood that this has been done for the purpose of facilitating disclosure of the invention and that this merely 110 exemplifies how the invention may be applied to one particular field of use, and it is desired to be understood that various changes 115 modifications, and additions may be made to adapt the invention to the particular problem 120 encountered in practicing the same, for instance, if desired, the invention may be used to indicate the positions of two entirely different 125 and separate instrumentalities, or the switch box contacts 5-6 may be connected to 130

one point of the track switch and the contacts 5—12 may be connected to the other point of the track switch, and other changes may be made without departing from the 5 spirit or scope of the invention or the idea of means underlying the same, all without departing from the present invention, except as demanded by the scope of the following claims.

10. What I claim as new is:—

1. Indicating means for indicating with a high degree of assurance the position of a distant traffic controlling device for railroads comprising, a polar relay responsive 15 only to direct current, a three-position alternating current relay responsive distinctively to alternating current of a particular polarity, a circuit including said polar relay and said three-position relay, and means controlled 20 by a distant traffic controlling device for causing the flow of alternating current having a particular phase relation and direct current of a particular polarity in said circuit at the same time.

25. 2. Indicating means for indicating with a high degree of assurance the position of a distant traffic controlling device for railroads comprising, a polar relay responsive only to direct current, a three-position alternating current relay responsive distinctively to alternating current of a particular polarity, a circuit including said polar relay and said three-position relay, means controlled by a distant traffic controlling device for causing 30 the flow of alternating current having a particular phase relation and direct current of a particular polarity in said circuit at the same time, and a control circuit controlled by said relays closed only when said relays assume 35 said corresponding positions.

40. 3. Indicating means for indicating with a high degree of assurance the position of a distant traffic controlling device for railroads comprising, a polar relay responsive only to direct current, a three-position alternating current relay responsive distinctively to alternating current of a particular polarity, a circuit including said polar relay and said three-position relay, means controlled 45 by a distant traffic controlling device for causing the flow of alternating current having a particular phase relation and direct current of a particular polarity in said circuit at the same time, and a control circuit 50 controlled by said relays closed only when said polar relay and said three-position relay assume specific energized positions.

45. 4. Indicating means for indicating with a high degree of assurance the position of a distant traffic controlling device for railroads comprising, a polar relay responsive only to direct current, a three-position alternating current relay responsive distinctively to alternating current of a particular polarity, a circuit including said polar relay,

and said three-position relay, two distant devices, means for causing the flow of alternating current of a particular phase relation in said circuit when one of said two devices assumes a particular position, and means for 70 causing the flow of direct current of a particular polarity in said circuit when the other of said devices assumes a particular position.

5. Indicating means for indicating with a high degree of assurance the position of a 75 distant traffic controlling device for railroads comprising, a polar relay responsive only to direct current, a three-position alternating current relay responsive distinctively to alternating current of a particular polarity, a circuit including said polar relay, and said three-position relay, two distant devices, means for causing the flow of alternating current of a particular phase relation in said circuit when one of said two devices assumes 80 a particular polarity in said circuit when the other of said devices assumes a particular position, and a partial circuit including contacts of said relays closed when such relays assume 85 said particular positions.

6. Means for indicating whether two distant traffic controlling devices assume particular and corresponding positions comprising, a three-position polarized alternating current relay, a three-position polar direct current relay, a circuit including said three-position relays, an alternating current source in said circuit, a rectifier in said circuit, means for reversing the connections of said alternating current in said circuit, means for reversing said rectifier in said circuit, and means controlled in accordance with the positions of both of said three-position relays.

7. Means for indicating whether two distant traffic controlling devices assume particular and corresponding positions comprising, a three-position polarized alternating current relay, a three-position polar direct current relay, a circuit including said three-position relays, means at the remote end of 105 said circuit for at times opening said circuit, and means controlled in accordance with the positions of both of said three-position relays.

8. Indicating means for indicating with a high degree of assurance the position of a 110 distant traffic controlling device for railroads comprising, an indicating circuit, indicating means in said circuit responsive only if two distinct kinds of current flow in said circuit, and means at a distant traffic controlling device for applying said two distinct kinds of current to said circuit when said traffic controlling device assumes a particular position.

9. Means for indicating whether two distant traffic controlling devices assume particular and corresponding positions comprising, a three-position polarized alternating current relay, a three-position polar direct current relay, a circuit including said three-position relays, means at the remote end of 120 125 said circuit for applying said two distinct kinds of current to said circuit when said traffic controlling device assumes a particular position.

said circuit for applying alternating current of a polarity corresponding to the position assumed by one of said devices and for applying direct current of a polarity corresponding to the position assumed by the other of said devices to said circuit.

10. Indicating means for indicating with a high degree of assurance the position of a distant traffic controlling device for railroads comprising, a polar relay responsive only to direct current, an alternating current relay responsive distinctively to alternating current of a particular polarity, a circuit including said polar relay and said alternating current relay, and means controlled by said distant traffic controlling device for applying alternating current of a particular polarity to said circuit and including in series in said circuit a rectifier poled in a particular direction when said traffic controlling device assumes a particular position.

11. Means for indicating whether two distant traffic controlling devices assume particular and corresponding positions comprising, a polar alternating current relay at a local office, a polar direct current relay at said local office, a circuit leading from said office to said two distant traffic controlling devices including said relays, and means for applying alternating current of a particular polarity to said circuit when one of said traffic controlling devices assumes a particular position and applying direct current of a particular polarity to said circuit when said other traffic controlling device assumes a particular position.

12. Means for indicating whether two distant traffic controlling devices assume particular and corresponding positions comprising, a polar alternating current relay at a local office, a polar direct current relay at said local office, a circuit leading from said office to said two distant traffic controlling devices including said relays, and means for applying current to said circuit of a polarity depending on the position of one of said traffic controlling devices and inserting a rectifier in said circuit poled in accordance with the position of said other traffic controlling device.

In testimony whereof I affix my signature.
50 OSCAR H. DICKE.
